UNITED STATES PATENT OFFICE

107,670

DESIGN FOR AN AIR CONDITIONING UNIT

John G. Zummach, Racine, Wis., assignor to Hexcel Radiator Company, Racine, Wis., a corporation of Wisconsin

Application April 29, 1937, Serial No. 69,036

Term of patent 3½ years

To all whom it may concern:

Be it known that I, John G. Zummach, a citizen of the United States, residing at Racine, in the county of Racine and State of Wisconsin, have invented a new, original, and ornamental Design for an Air Conditioning Unit, of which the following is a specification, reference being had to the accompanying drawing, forming a part thereof.

Figure 1 is a front perspective view; and
Figure 2 is a rear perspective view of an air conditioning unit showing my new design.

I claim:

The ornamental design for an air conditioning unit, as shown.

JOHN G. ZUMMACH.
